UNITED STATES PATENT OFFICE.

ARTHUR L. RUSSELL, OF BOSTON, MASSACHUSETTS, ASSIGNOR TO UNITED SHOE MACHINERY COMPANY, OF PATERSON, NEW JERSEY, A CORPORATION OF NEW JERSEY.

SHOE.

1,124,959.

Specification of Letters Patent.

Patented Jan. 12, 1915.

Original application filed December 17, 1910, Serial No. 597,851. Divided and this application filed November 20, 1913. Serial No. 802,157.

To all whom it may concern:

Be it known that I, ARTHUR L. RUSSELL, a citizen of the United States, residing at Boston, in the county of Suffolk and State 5 of Massachusetts, have invented certain Improvements in Shoes, of which the following description, in connection with the accompanying drawings, is a specification, like reference characters on the drawings indicating like parts in the several figures.

This invention relates to the manufacture of boots and shoes and this application is a division of an application Serial No. 597,851, filed Dec. 17, 1910, for improvements in the 15 manufacture of boots and shoes. A present general practice is to overwork the upper into lasted position about the toe end of the last by wipers that have acting edges shaped to embrace the toe portion of the shoe and 20 lay the upper over the margin of the inner-sole to which it is tacked in McKay shoes. The innersoles of welt and turn shoes are provided with upstanding lips or other formations that present a shoulder against 25 which the upper is lasted. A binder of wire or other continuous material has been generally employed to secure the upper in lasted position by anchoring it at one end to a tack and drawing it tightly about the up- 30 per around the toe to bind it against the shoulder of the innersole after which it is anchored under tension to another tack.

One object of this invention is to improve shoes in respect to the retention of the up- 35 per in lasted position, or to both the shaping and the retention of the upper, particularly at the end of the shoe.

A feature of this invention consists in the combination with a shoe upper an end portion 40 of which is overworked about the end of the last or a form, of means secured exclusively to the surface of the overworked upper to maintain the upper in overworked position.

Another feature of the invention consists 45 in a shoe having an upper the margin of which at one end of the shoe is gathered inwardly into position to overlie the innersole and is permanently shrunk on a curved line 50 located to come inside the edge of the innersole and shorter than the edge line of the innersole to form a toe pocket, or it might be a heel pocket, in the upper.

Either of these features may be employed

separately or both together, the invention 55 being illustrated in the accompanying drawings as embodied in a lasted toe portion of a shoe having both features, although it will be understood that the invention is applicable not only to the lasting operation as 60 generally practised but also to the preparatory formation of toes and heels preliminary to assembling with an innersole on a last.

A binder is herein shown as a non-metallic 65 strip of suitable proportions which is provided with an adhesive by which it sticks to the upper. It will be readily understood that the binder holds the upper over the end of the toe largely by confining it in over- 70 wiped position and that for serving this purpose the binder may be caused to adhere at its ends only at the sides of the toe. Preferably, however, the binder will be made adhesive throughout its length and by stick- 75 ing to the upper it will prevent the upper from slipping under it at any point. It may be sewed into the shoe and thus continue permanently to bind the upper over the toe.

The adhesive used on the binder may be 80 of any suitable kind although it will advantageously be one of the varieties that are non-sticky while dry and at ordinary temperatures. In accordance with a further feature of the invention the binder is coated 85 with an adhesive that is rendered sticky by heat and the lasting apparatus or other means by the aid of which it is applied may conveniently include means for heating the binder to cause the adhesive to stick to the 90 shoe upper as fully explained in said co-pending application.

The shrinking of the flange of the upper to contract it and reduce the elasticity of the leather for the purpose described is done 95 by local application of heat to the upper leather along the line or strip which it is desired to contract. The heat treatment stiffens the leather more or less on that line and, by the contraction and by the stiffening 100 and the loss of elasticity, reduces the tendency of the margin to slack back and therefore assists in forming a permanent toe pocket in the upper. If an adhesive binder is applied to this flange, as above described, 105 reaction of the flange from its shaped condition is very fully prevented.

These and other features of the invention

will appear more fully from the following detailed description and will then be pointed out in the claims.

Figure 1 shows the toe portion of a welt shoe having the upper treated and secured in accordance with this invention; Fig. 2 is a perspective view of the binder; Fig. 3 shows a McKay shoe embodying this invention.

10 In making a shoe embodying this invention, apparatus such for example as that shown in said co-pending application Serial No. 597,851 may be used. This machine includes toe lasting wipers of usual type which 15 are used as is customary, and as fully explained in said application, to gather the margin of the end portion of the upper into lasted position over the toe of the innersole, or a last, or it might be any toe or a heel 20 form, to produce a flange and if they are heated they will smoothly iron the flange and heat it to prepare it for the adhesive binder to stick effectively to it. When the wipers are partially backed away 25 from the shoulder 32 of the innersole or from the upstanding portion 34 of the upper which they have pressed against the shoulder, a strip or strand 30 of binding material coated with adhesive on its back 30 will be placed about the toe in the space opened up by backing off the wipers. This strip may advantageously be thin fabric or paper rendered stiff by the adhesive and capable of standing on edge with the adhesive against the upstanding portion 34 of 35 the upper. If the upper has become heated by the wipers, that heat may be sufficient to cause the binder to adhere to the upper. The binder may be further heated, particu- 40 larly at its end portions. For this purpose end rubbers, *e. g.*, such as are shown and described in said application Serial No. 597,851 may be used and advantageously the heated wipers may be again advanced to 45 force the binder into intimate contact with the upstanding upper and to heat and soften the adhesive to make it stick. The binder heating means may remain in contact with the binder only for the necessary time to 50 allow the heat to act on the adhesive and then be partially backed away where the wipers continue to hold the upper from slackening back while the adhesive sets into holding condition.

55 The action of the heated wipers may be more than enough to soften and smoothly iron the upper. The wipers may advantageously be sufficiently heated and left standing in contact with the work long enough, 60 as in said partially backed off position, to shrink or contract the flange as at 33 and substantially reduce the elasticity of the portion so shrunk. This contraction will occur, in case they are left standing on the 65 upper after having been partially backed

away from the binder, on a line extending around the toe inside of the curved edge line of the innersole, and therefore shorter than said edge line, and will assist in rendering permanent the toe pocket in the upper. The 70 heat treatment of the upper also stiffens the flange of the upper more or less which further assists in rendering its shape permanent. The shrinking of the flange of the upper for the purpose described might, ob- 75 viously, be effected in other ways than that described, as for example by the use of some other heated instrument than the wipers, such as a crescent shaped branding iron applied to the flange after the wipers have 80 been backed away to uncover the portion that is to be shrunk by heat.

The stiffening of the stock by heat prefer- 85 ably does not extend over or is at a minimum at the rounded edge of the shoe and, as will be understood, the binder when used protects from the stiffening action of the heat the portion of the upper through which the inseam stitches are to be made in a welt shoe. In a McKay shoe, Fig. 3, the usual 90 location for the stitching line is inside of where it would be desirable to have the maximum effect of the heat.

The heel end portion of an upper may be treated similarly to the toe by the action of 95 heat to contract and stiffen the overwiped flange, or by fastening it with a binder secured exclusively to the surface of the over-worked upper to maintain it in overworked position, the binder for the heel being ad- 100 vantageously a crescent or other similarly shaped piece of fabric coated on its lower side with adhesive.

The improvement in methods of making 105 shoes herein disclosed is claimed in a co-pending application Serial No. 711,648, filed July 26, 1912, and the improvement in toe binders herein disclosed is claimed in co-pending application Ser. No. 711,647, filed July 26, 1912.

Having explained the nature of the present invention, I claim as new and desire to secure by Letters Patent of the United States:

1. The combination with a shoe upper the 115 toe portion of which is overworked around the toe end of the last and over upon the margin of the toe of the innersole and is free from fastenings connecting it to the innersole, of a narrow non-metallic binding strip or band curved around the toe and united exclusively to the outer surface of the overworked upper inside the edge of the innersole on a line shorter than the original edge line of the toe portion of the vamp.

2. The combination with a shoe upper the 120 toe portion of which is overworked around the toe end of the last and over upon the feather and against the lip of the toe of a 125 welt innersole, of a non-metallic toe binder 130

in the form of a narrow strip united by adhesive at its end portions and also intermediate its end portions to the outer surface exclusively of the upper between said inner-
5 sole lip and the edge of the shoe bottom.

3. The combination with a shoe upper the toe portion of which is overworked around the toe end of the last and over upon the feather of an innersole to present an upper
10 standing flange against the lip or shoulder of the innersole, of a toe binder comprising an adhesive coated strip standing on edge with its coated face against and united by the adhesive to the said upstanding flange
15 of upper.

4. The combination with a shoe upper the toe portion of which is overworked around the toe end of the last and gathered inwardly over upon the margin of the toe of the innersole, of a toe binder in the form of a narrow strip coated with adhesive that is non-sticky at normal temperatures and has been made by heat to unite the binder permanently to the outer surface exclusively of
20 the inwardly gathered margin of the over-worked upper in position to hold said margin in overworked relation to the last, said binder being of non-metallic material whereby it offers no obstruction to a subsequent sewing or inseam trimming operation on the shoe.
25

5. In a shoe the combination with an upper the toe portion of which has been lasted about the toe of a last and the fringe
30 of which has been gathered inwardly from the end and sides of the toe of the last to form the toe pocket of the shoe, of a binder of narrow non-metallic sheet material united to the upper around the end of the toe and exclusively to the outer face of the gathered
35 fringe of the upper and adapted to be sewed into the welt or sole attaching seam and become a permanent part of the shoe.

6. In a shoe the combination with an upper the toe portion of which has been lasted about the toe of a last and the fringe of which has been gathered inwardly from the end and sides of the toe of the last to form the toe pocket of the shoe and is free
40 from any fastenings connecting it to an innersole upon the last bottom, of a narrow strip of sheet material permanently united to the outer face exclusively of said gathered fringe around the end of the toe and located exclusively between the edge of the toe and the edge of the inwardly gathered fringe of the upper.
45

7. In a shoe, an innersole and an upper lasted over the margin of the curved end of the innersole and permanently shrunk on a curved line extending around the end of the innersole and shorter than the edge line of the innersole to form with the innersole a toe pocket.
50

65 8. In a shoe, an upper having the margin

of an end portion gathered inwardly to overlie an innersole and permanently shrunk on a curved line located to come inside the edge of the innersole and shorter than the edge line of the innersole to form a toe pocket.
70

9. In a shoe, an upper having the margin of an end portion gathered inwardly for forming a flange to overlie the curved end of an innersole, said flange being shrunk and stiffened along a curved line located to come inside the edge of the innersole end and shorter than the edge line of said innersole end.
75

10. In a shoe, an upper having the margin of an end portion gathered inwardly for forming a flange to overlie the curved end of an innersole, said flange being shrunk and stiffened along a curved line located to come inside the edge of the innersole end and shorter than the edge line of said innersole end, and a binder applied to the flange also on a line shorter than said edge line to hold the upper from returning from the shape given to it.
80

11. The combination with a shoe upper, an end portion of which is overworked about the end of the last, of a narrow curved strip of binding material secured exclusively to the outer surface of the over-worked upper between the edge of the shoe bottom and the edge of the fringe of the upper to maintain the upper in overworked position.
85

12. In a shoe, an upper of elastic material one end portion of which is shaped to conform to the contour of an end of a last and present a flange extending inwardly over the margin of the last bottom and has the elasticity of the shaped portion of the material that lies upon the last bottom reduced on a line embracing the end of the shoe bottom relatively to that portion of the upper which surrounds the side faces of the last end.
95

13. In a shoe, an upper the margin of one end portion of which is gathered inwardly and ironed down to constitute a flange to overlie the curved end portion of the shoe innersole, said flange being permanently stiffened and shrunk on a line embracing the last end and relatively to the adjacent part of the upper lying against the side faces of the last end, substantially as described, to set the flange in lasted position.
110

14. A welt shoe comprising an innersole having a feather and a lip, an upper having its margin gathered and lasted inwardly over the feather and against the lip of the toe portion of the innersole, and a narrow non-metallic toe binding strip secured to the outer surface only of the upper between the edge of the innersole and said lip around the toe and maintaining the upper in lasted relation to the innersole.
115

15. A welt shoe comprising an innersole

130

having a feather and a lip, and an upper having its margin gathered and lasted inwardly over the feather and against the lip of the toe portion of the innersole, 5 said upper being locally shrunk along a line located between the edge of the innersole and said lip and extending around the toe as and for the purpose described.

In testimony whereof I have signed my name to this specification in the presence 10 of two subscribing witnesses.

ARTHUR L. RUSSELL.
